UNITED STATES PATENT OFFICE.

GEORGE S. COX, OF FITZWATERTOWN, PENNSYLVANIA, ASSIGNOR TO HIMSELF AND WALTER S. COX, TRADING AS GEORGE S. COX AND BROTHER, OF PHILADELPHIA, PENNSYLVANIA.

HAIRCLOTH-LOOM.

No. 834,000.

Specification of Letters Patent.

Patented Oct. 23, 1906.

Application filed June 13, 1905. Serial No. 264,992.

To all whom it may concern:

Be it known that I, GEORGE S. Cox, a citizen of the United States, residing at Fitzwatertown, county of Montgomery, and State 5 of Pennsylvania, have invented a new and useful Improvement in Haircloth-Looms, of which the following is a full, clear, and exact description, reference being had to the accompanying drawings, which form a part of 10 this specification.

My invention relates to looms, and more particularly to that type of loom adapted to the manufacture of that variety of haircloth in which a pick of hair and a pick of yarn are 15 contained in each shed of warp, as shown, described, and claimed in Letters Patent issued to me September 13, 1904, No. 769,790. A loom adapted to weave such a cloth is shown, described, and claimed in Letters Patent 20 issued to me July 18, 1905, No. 795,249.

The present invention is an improvement on the loom of the last-mentioned patent, and has for its special object to stop the rotation of the take-up mechanism in case the 25 nipper fails to grasp an end of yarn, thereby preventing the warp feeding forward until after a pick of yarn is thrown.

The invention also has for its object to cause the loom to be stopped in the event 30 that the nipper misses more than a determinate number of successive picks of yarn.

The invention also has for its object to provide a nipper that is capable of simultaneously grasping with the requisite tightness two or 35 more picks of weft of substantially different thickness, more specifically a pick of hair and a pick of yarn.

The invention consists of the means hereinafter described and claimed for effecting 40 the stated objects.

Figure 1 is a side elevation of the loom. Fig. 2 is a front elevation. Fig. 3 is a detail plan view of the ratchet mechanism operated when the nipper fails to grasp an end of yarn. 45 Fig. 4 is a detail view, in side elevation, of the gravity-lever and associated mechanism operated when the nipper fails to grasp an end of yarn. Fig. 5 is a perspective view of the belt-shifting control-lever and the mechanism 50 by which it is immediately actuated. Fig. 6 is a plan view of the jaw end of my improved nipper. Fig. 7 is a side elevation of the nipper of Fig. 6.

a is a frame of the loom, having suitable bearings for the studs of the lay *b* for the 55 spindles of the warp-beams *c*, cloth-roller *d*, and take-up rollers *d'* and *d''* and for the shafts of ratchet-wheel *e* and crank-shaft *f*.

g is a spur-gear on the shaft of ratchet-wheel *e*. 60

h is a spur-gear on the spindle of the take-up roller *d'*.

i j k l are the gears connecting gears *g* and *h*. *d³* is another gear on the shaft of roller *d'*, 65 engaging a gear *d⁴* on the shaft of roller *d''*.

d⁵ is a pulley on the shaft of roller *d''*.

d⁶ is a pulley on the shaft of the cloth-roller *d*, and *d⁷* is a belt connecting pulleys *d⁵* and *d⁶*.

The ratchet-wheel, which is operated by the lay in the usual manner, as hereinafter 70 described, operates the take-up rollers *d'* and *d''* through the chain of gearing above set out, and the roller *d''* operates the cloth-roller *d* by means of the belt-and-pulley connection described. The cloth from the loom passes 75 down to, under, and partially around take-up roller *d'*, thence up to, over, and partially around take-up roller *d''*, and thence down to the cloth-roller. The take-up rollers *d'* and *d''* are roughened.

To avoid confusion in the drawings, the usual well-known mechanism for operating the lay is not shown.

t is the usual trough or receptacle containing 80 separate strands of horsehair.

r is the yarn-carrier for the linen, cotton, or other yarn which it is designed to use in connection with the hair, as above stated, to form the weft of the compound cloth. The specific construction of this yarn-carrier is 90 substantially the same as that set forth in Letters Patent issued to me July 18, 1905, No. 795,250, and will be hereinafter more fully described. *n* is the nipper, the action of which, as set forth in said Letters Patent 95 No. 795,249, is to grasp one end of a strand of hair that has been previously selected from the trough by the selector *s* and an end of yarn that has been fed from the yarn-carrier *r* and pull them together across the loom.

100 11 is a slide by which the hair-trough *t* is supported. The slide 11 has a limited movement to and fro on the loom-frame. The trough *t* is directly under the selector, so that at each reciprocation of the selector a strand 105 of hair will be selected from the trough and

presented to the nipper at the beginning of its throw. The outfeed eye of the yarn-carrier extends opposite the jaw of the selector, so that the yarn extending therethrough will 5 be in position to be grasped by the nipper at the same time that the latter grasps a strand of hair picked by the selector.

The trough is given the usual reciprocating motion by means of a connecting-rod *m*, pivoted at one end on the slide 11 and at the other end on the gear *o*, which is driven by the gear *p*, the shafts of both gears turning in bearings on the loom-frame. Fixed to the shaft of gear *p* is the ratchet-wheel *q*, which 15 is turned by the pawl *u*, pivoted on the upper end of the lever *v*. The lever *v* is pivoted between its ends on the shaft of gear *p*, the lower end of lever *v* being connected by the link *w* with the lay *b*. The lay thus imparts 20 to the lever *v* a constantly-reciprocating motion, thus causing the pawl *u* to turn the ratchet *q* tooth by tooth. This movement of the ratchet-wheel imparts, through gears *p* and *o* and connecting-rod *m*, an alternate 25 step-by-step advancing motion and a step-by-step receding motion to slide 11 and trough *t*, thus bringing all sections of the trough immediately under the selector.

I will now describe the mechanism for actuating the ratchet *e*, which, as above described, actuates the take-up mechanism.

58 is a bracket secured to the lay.

56 is a lever pivoted at its lower end to the frame of the loom and connected at its upper 35 end by rod 57 with the bracket 58.

55 is a pawl pivoted to the lever 56. This pawl is the operative pawl for the ratchet *e*, turning the latter at each forward stroke of the lay. During the operation of the pawl 40 55 the pawl 60, pivoted between its ends to the loom-frame, acts as a holding-pawl.

It is necessary to cut off the yarn at or about the time of (preferably just before) the completion of the throw of a pick of hair and 45 yarn by the nipper *n*. To effect this, I provide a cutter or shears, one blade 61 of which is connected to the loom-frame, while the other blade 62 is pivoted to blade 61 and connected, by means of a link 63, with the 50 end of the bell-crank lever 64. The other end of the bell-crank is connected by a link 65 with the lower end of an intermediately-pivoted lever 66, the upper end of which carries the roller 67.

55 68 is a cam on the crank-shaft, having an abrupt descent from its highest to its lowest point, so that as the roller 67 overrides its highest point the spring 69, acting upon the lower end of the lever 66, is free to draw that 60 end of the lever 66 back rapidly, thus through link 65, bell-crank 64, and link 63 drawing down the cutting end of blade 62 of the shears and severing the yarn. Immediately thereafter the cam 68 again acts upon the roller 67 to move the lever 66 to its illus-

trated position, thus again opening the blades of the shears.

The selector *s* is of a well-known construction. It consists of the part 90, vertically movable in guides 92 and carrying the fixed 70 jaw, and the part 91 hinged to the part 90 and carrying the movable jaw.

97 is a shaft secured to which is the bevel-gear 76, engaged and driven by the bevel-gear 77 by means of connections from the 75 crank-shaft. (Not shown, but well understood by those familiar with haircloth-looms.) Secured to shaft 97 is the cam 95 and the crank-disk 98.

99 is a connecting-rod between disk 98 and 80 part 90, whereby the selector is reciprocated vertically.

93 is a lever pivoted between its ends to the bracket 94, one end of the lever engaging part 91 and the other end the cam 95. When the upper end of lever 93 is brought opposite the low point of the cam 95, the spring 96 at once moves the lever 93 so as to engage the part 91 of the selector and move it on its hinge to open the jaws. As the upper end of 90 lever 93 rides up onto the high point of the cam 95 the lever 93 is retracted from the part 91 of the selector, permitting it to drop to close the jaws.

The yarn-carrier *r* is of substantially the 95 same construction as set forth in said Letters Patent No. 795,250. The supporting means for the yarn-carrier consists of a rod 102 in guides 103 103, secured to the loom-frame. The yarn-carrier itself consists of a plate 104, having a bracket 105, to which is secured a tube 106. The yarn extends from the bobbin 107 down through the spout 106' and through an eye 109 on the upper end of a bracket 111, secured to the bracket 105, thence through 105 an eye on the lower end of a bracket 112, secured to the guide 92, and thence into the upper end of the tube 106 and out through its open lower end.

110 110 is a pipe connected with the air-blast and also communicating with the tube 106. The effect of the blast of air is to cause the free end of the yarn projecting beyond the lower end of the tube to be blown out straight in a direction coincident with the direction of 115 extension of the tube 106, which, as shown, is vertical. The tube 106 is located immediately opposite and somewhat above the selector *s* and directly over the line of travel of the nipper *n*, so that as the nipper moves forward to grasp a strand of hair and the free end of the yarn the latter will be in the precise position required for causing it to be grasped by the nipper. If for any reason the nipper fails to grasp an end of yarn, it is 120 desirable, if not necessary, to prevent the warp feeding forward until after the pick of yarn is thrown. This is effected by stopping the rotation of the ratchet-wheel *e* and the chain of mechanism driven thereby for driv- 125 130

ing the take-up rollers. The rotation of the ratchet-wheel *e* is stopped by lifting the holding-pawl 60, as without this pawl the tension of the take-up rollers is effective to return the ratchet-wheel after it is moved forward by the pawl 55.

To lift the holding-pawl 60, the following mechanism is provided: 113 is a lever pivoted at one end to the frame of the head-motion of the loom, its other end normally resting on an adjustable screw 119, engaging a bracket 120, secured to the loom-frame. 114 is a connecting-rod pivoted at its upper end to the lever 113 and at its lower end to 15 one end of the lever 115. The lever 115 is pivoted between its ends to the loom-frame. 116 is a link connecting the other end of lever 115 with the rear end of holding-pawl 60. When the lever 113 is raised, it depresses the 20 rear end of pawl 60 by means of the connections specified and raises the pawl off the ratchet *e*.

To raise the lever 113, the following mechanism is provided: 117 is a ratchet-wheel turning loosely on a stud fastened to a bracket on the loom. 118 is a pawl-lever pivoted near its actuating end on the lever 113 and resting on the bracket 120, secured to the loom-frame. The normal position of 25 the pawl-lever is that illustrated in Fig. 1, in which the pawl is just out of engagement with the ratchet-wheel 117. 125 is a rod pivoted at its upper end to the pawl-lever 118. When the rod 125 is elevated, the 30 first action is for the pawl to drop behind one of the teeth of the ratchet-wheel. Continued upward movement of the rod 125 causes the ratchet-wheel to advance one tooth. As soon as the pawl contacts with 35 the ratchet-wheel it can no longer turn on its pivot, so that while the ratchet-wheel is being turned the distance of one tooth the pawl-lever 118 is lifted bodily, thereby raising lever 113. As before described, the raising 40 of lever 113 lifts the holding-pawl 60 off the ratchet-wheel *e*.

To the lower end of rod 125 is pivoted a lever 121, notched near its lower end. (See Fig. 4.) Pivoted to the loom-frame is a lever 50 84, having a boss engaging a cam 86 on the crank-shaft. As the cam 86 rotates the lever 84 is raised, and the knife-edged lug on the free end of the lever 84 is adapted to engage the notched lever 121, thereby raising 55 rod 125 and through the connections before described lifting holding-pawl 60 out of contact with the ratchet-wheel *e*. Normally, however, the notched lever 121 just before the lever 84 rises has been moved into the position shown in Figs. 1 and 4 and is not in position to be engaged by the lug on the end of said lever 84. The movement of the notched lever 121 into this inoperative position takes place whenever the nipper succeeds in grasping 60 an end of yarn. As the yarn is pulled

across the loom by the nipper it engages and elevates the finger 122, as hereinafter described. This finger is secured to one end of a shaft 123, turning in bearings in a bracket on the loom-frame. To the other end of this 70 shaft is secured an arm 124. As the finger 122 is raised it causes the arm 124 to engage and move the notched lever 121 into its illustrated inoperative position. The yarn is caused to so elevate the finger 122 by imparting to the yarn-carrier support at the proper time an upward movement, which is effected by pivoting to the top of rod 102 one 75 end of a connecting-rod 70, the other end of which is connected to the outer end of the 80 lever 701, which is pivoted to the outer end of a bracket 71.

73 is a bracket secured to lever 701 and having a roller 74, which contacts with the cam 75, secured to the shaft 97. By means 85 of the cam 75 and the mechanism actuated thereby the rod 102 is caused to move up at the proper time, causing the yarn as it is pulled across the loom by the nipper to rise, thereby moving the notched lever 121 out of 90 operative position, as before described. When, however, the nipper fails for any reason to grasp an end of yarn, there is nothing to move the notched lever 121 into its illustrated position, and it consequently drops 95 down into a vertical position (the finger 122 being out of line of the hair in the movement of the latter across the loom) with its notch in position to be engaged by the lever 84, with the result that the rod 125 is lifted, thereby 100 through the mechanism before described causing the holding-pawl 60 to be lifted from the ratchet-wheel *e*.

The mechanism so far described is all that is essential to insure a stoppage of the feed of 105 the warp or cloth when the nipper fails to grasp an end of yarn. It is obvious, however, that without any additional mechanism if for any reason the yarn-throwing mechanism becomes seriously deranged the result 110 will be that for a number of consecutive throws of the nipper no yarn will be thrown. At the same time, however, the nipper will continue to grasp and pull through a strand of hair at each reciprocation, thereby causing 115 a number of picks of hair to be bunched together in the same shed of warp. It is necessary to prevent this contingency. The most effective way of doing so is to stop the loom in the event that any such condition 120 arises, so that the trouble with the yarn-carrier, whatever it may be, may be discovered and repaired. I have accordingly provided 125 mechanism in addition to that hereinbefore described whereby in case the nipper fails to grasp and pull through an end of yarn for three consecutive reciprocations of the nipper the loom will be brought to a stop. This mechanism I will proceed to describe.

126 is a holding-pawl engaging the ratchet- 130

wheel 117. This holding-pawl is pivoted on a bracket on the loom-frame. 127 is a lever pivoted on another bracket on the loom-frame and connected between its ends by 5 means of a flexible connection 128 with the holding-pawl 126.

129 is a rod connected at its upper end to the end of lever 127 and at its lower end to one end of a lever 130. The lever 130 is pivoted at its other end to the loom-frame and between its ends is provided with a lug engaging a cam 131 on the crank-shaft. The holding-pawl 126 is normally in engagement with the ratchet-wheel 117, but through the 15 connections described is lifted out of engagement with the ratchet 117 at every revolution of the crank-shaft and at a time following the engagement of the pawl-lever 118 with the ratchet-wheel and is allowed to 20 turn into engagement with the ratchet-wheel 117 before the pawl-lever 118 is disengaged therefrom.

From the foregoing description it will be understood that if the nipper at one reciprocation fails to pull through an end of yarn the first action is to turn the ratchet-wheel 117. Thereafter when the lug on lever 84 drops onto the low point of its actuating-cam the pawl-lever 118 and the lever 113 are 25 returned to their normal positions. Ratchet-wheel 117 continues to be held in its advanced position by reason of its engagement with the holding-pawl 126. If at the next reciprocation of the nipper an end of yarn is 30 pulled through, the rod 125 is not again elevated, and the holding-pawl 126 is lifted out of engagement with the ratchet-wheel 117, causing the ratchet-wheel to be returned to its original position by mechanism to be hereinafter described. If, however, the nipper at its second reciprocation fails to pull through an end of yarn, the rod 125 is again operated, causing the pawl-lever 118 to again engage the ratchet 117 and advance it another tooth. 35 In this event the disengagement of the holding-pawl with the ratchet-wheel 117 will not permit the ratchet-wheel to return to its original position, as during the disengagement of the holding-pawl 126 the ratchet-wheel 117 40 is being advanced by the pawl-lever 118. In the same way if the nipper fails to pull an end of yarn for the third successive time the pawl-lever 118 will advance the ratchet-wheel 117 a third tooth. When the ratchet-wheel 117 is so advanced the third tooth, the mechanism for stopping the loom is brought 45 into operation.

132 is a lever secured to the loom-frame at one end and having between its ends a slot 60 133, engaging a pin 134 on the ratchet-wheel 117.

135 is a spring secured at one end to the loom-frame and at the other end near the outer end of lever 132.

65 When the ratchet-wheel 117 is advanced,

as before described, a distance of one tooth, the lever 132, through the pin-and-slot connection described, is raised a certain distance. If on the next reciprocation of the nipper an end of yarn is pulled through, the disengagement of the holding-pawl 126 from ratchet-wheel 117 permits the spring 135 to return the lever 132 to its normal position, thus causing the ratchet-wheel to also return to its normal position. Further downward movement of the lever 132 is prevented by the engagement of pin 134 with the end of the slot 133. In the same way if the nipper on only two successive reciprocations fails to pull through an end of yarn the spring 135 70 will return the lever 132 to its original position. If, however, the nipper for three successive reciprocations fails to pull through an end of yarn, the lever 132 will be elevated to a sufficient height to bring into operation a 75 chain of mechanism for stopping the loom. This chain of mechanism consists of the following: Secured to the end of lever 132 is a rod 136. The lower end of rod 136 is pivoted to the end of a crank 137, secured to 80 a shaft 138, turning in bearings on the lay. (See Fig. 5.) Secured to the shaft is a lug 139. 140 is a tripping-lever fulcrumed between its ends on the breast-beam of the loom. 141 is an ear on the lever 140. The ear 141 has a bifurcated end adapted to be engaged by the lug 139. The normal position of the lug 139 is such that as the lay advances the lug will pass under the ear 141. If the ratchet-wheel 117 turns a distance of 85 one tooth or of two teeth, the lever 132 and rod 136 will not be raised a distance sufficient to turn the shaft 138 sufficiently to cause the lug 139 to engage the ear 141; but if the ratchet-wheel 117 is advanced a distance of 90 three teeth then the lever 132 and rod 136 are raised a distance sufficient to turn the shaft 138 so that the lug 139 is raised to a level with the ear 141. Consequently at 95 this reciprocation of the lay the lug 139 engages the ear 141 and turns the lever 140 about its fulcrum. This movement of the lever causes it to engage the belt-shifting control-lever 142, which controls the shift of the belt from the fixed to the loose pulley, 100 and stops the loom, as will now be described. 105

The control-lever 142 is of ordinary construction, having its lower end formed of spring metal and normally resting when the loom is in operation in a notch 143 at the 110 rear of a slot 144, formed in a bracket on the loom-frame. To stop the loom, the lever 142 is moved out of the notch 143 into the rear end of slot 144 and then by its own spring tension moves to the front of the slot. 115

145 is the usual belt-shifting lever fulcrumed between its ends on a bracket fastened to the loom-frame.

When, as before described, the lever 140, by reason of the engagement of lug 139 with 120

ear 141, turns on its fulcrum and engages the control-lever 142, it moves the latter out of the notch 143 into the slot 144, the lever 142 then moving by its own spring tension to the front of the slot, thereby actuating the lever 145 to shift the belt from the tight pulley to the loose pulley. At the same time that the loom is stopped the holding-pawl 126 is lifted out of engagement with the ratchet-wheel 117, thereby permitting all the parts to return to their normal positions.

The disengagement of the holding-pawl 126 is effected by the following means: 146 is a lever fulcrumed between its ends to the loom-frame. One end of this lever is in position to be struck by the control-lever 142 as it moves toward the front of the slot. The other end of the lever 146 is provided with a wedge-shape cam 147. When the lever 146 is struck and moved by the lever 142, the cam 147 moves under the end of lever 130, thereby through rod 129, lever 127, and flexible connection 128 lifting the holding-pawl out of engagement with the ratchet-wheel 117.

The nipper employed by me is of peculiar construction and is particularly adapted for use in the manufacture of cloth in which a pick of hair and an end of yarn are grasped simultaneously. The nipper as ordinarily constructed operates so unsatisfactorily as to be practically unavailable. It is obvious that if the nipper simultaneously grasps a pick of yarn and a pick of hair its jaws will approach each other only to the extent permitted by the thickness of the yarn, the yarn being the thicker material of the two. Consequently the jaws will not approach sufficiently to secure and hold the hair. In my improved nipper I have provided means whereby the jaws will effectively grasp the yarn and the hair. This I accomplish by the following constructions, (see Figs. 6 and 7:) An inset 150 is formed in the fixed jaw 151 of the nipper. 152 is a flat spring-plate secured in the inset so that its top surface lies flush with the gripping-surface of the jaw. 153 is another and deeper inset in the fixed jaw. The front end of the spring overlies the inset 153. 154 is the movable jaw of the nipper.

The arrangement of the yarn-carrier is such that the yarn is caused to be grasped by the nipper at a point opposite the overhanging end of the spring. As the movable jaw closes upon the fixed jaw the yarn depresses the overhanging end of the spring, thereby enabling the gripping-surface of the movable jaw to approach sufficiently near to the gripping-surface of the fixed jaw to cause a strand of hair to be effectively grasped. The movable jaw is provided with the usual cam 155 and the usual spring 156, tending to move the movable jaw into its closed position.

Having now fully described my invention,

what I claim, and desire to protect by Letters 65 Patent, is—

1. In a loom, in combination, a hair-trough, a selector, a yarn-carrier, a nipper adapted to grasp an end of hair presented by the selector and an end of yarn presented by the yarn-carrier and pull them across the loom, the take-up mechanism, means to render the take-up mechanism inoperative, a finger adapted when engaged by weft to be actuated to render said means inoperative, 75 said finger being out of line of the hair in the movement of the latter across the loom, and means to actuate the yarn-carrier to cause the yarn fed therefrom in its movement across the loom to engage said finger. 80

2. In a loom, in combination, a nipper adapted to grasp an end of weft and pull it across the loom, a yarn-carrier adapted to present an end of yarn to the nipper, the take-up mechanism, means to render the 85 take-up mechanism inoperative, and belt-shifting mechanism actuated by said means.

3. In a loom, in combination, a nipper adapted to grasp an end of weft and pull it across the loom, a yarn-carrier adapted to 90 present an end of yarn to the nipper, the crank-shaft, belt-shifting mechanism, a lever adapted to be moved out of operative position by the yarn pulled across the loom by the nipper, means operated by the shaft to 95 operate said lever when the latter is not so moved out of operative position, and mechanism interposed between the lever and the belt-shifting mechanism whose operation is controlled by the operation of the lever. 100

4. In a loom, in combination, a nipper adapted to grasp an end of weft and pull it across the loom, a yarn-carrier adapted to present an end of yarn to the nipper, belt-shifting mechanism, and means to operate 105 the belt-shifting mechanism adapted to be operated when the nipper fails to grasp an end of yarn a definite number of consecutive times.

5. In a loom, in combination, a nipper 110 adapted to grasp an end of weft and pull it across the loom, a yarn-carrier adapted to present an end of yarn to the nipper, the take-up mechanism, the crank-shaft, connections therefrom to the take-up mechanism 115 adapted to render the latter inoperative, a lever included in said connections adapted to be moved by the yarn pulled across the loom by the nipper and thereby actuated to render said connections inoperative, belt-shifting 120 mechanism, and means actuated by said connections to operate said belt-shifting mechanism.

6. In a loom, in combination, a nipper adapted to grasp an end of weft and pull it 125 across the loom, a yarn-carrier adapted to present an end of yarn to the nipper, the take-up mechanism, a ratchet-wheel, and an ac-

- tuating-pawl therefor, a holding-pawl therefor, the crank-shaft, connections from the shaft to the actuating-pawl adapted to be operated when the nipper fails to insert an end of yarn, connections from the actuating-pawl to the take-up mechanism adapted when operated to render the take-up mechanism inoperative, belt-shifting mechanism, and connections from the ratchet-wheel adapted, when the ratchet-wheel is turned a determinate distance, to engage and operate the belt-shifting mechanism.
7. In a loom, in combination, a nipper adapted to grasp an end of weft and pull it across the loom, a yarn-carrier adapted to present an end of yarn to the nipper, a lever, the crank-shaft, connections from the shaft to the actuating-pawl adapted to be operated when the nipper fails to insert an end of yarn, a holding-pawl, means to release the holding-pawl after the actuating-pawl engages the ratchet and to return the holding-pawl into operative position before the actuating-pawl disengages, a spring adapted to return the ratchet to its normal position when engaged by neither of said pawls, belt-shifting mechanism, and connections from the ratchet adapted, when the latter is turned a determinate distance, to engage and operate the belt-shifting mechanism.
8. In a loom, in combination, a nipper adapted to grasp an end of weft and pull it across the loom, a yarn-carrier adapted to present an end of yarn to the nipper, a ratchet-wheel, an actuating-pawl therefor, the crank-shaft, connections from the crank-shaft to the actuating-pawl adapted to be operated when the nipper fails to insert an end of yarn, a holding-pawl, means to release the holding-pawl after the actuating-pawl engages the ratchet and to return the holding-pawl into operative position before the actuating-pawl disengages, a lever actuated by the ratchet, belt-shifting mechanism, an ear thereon, the lay, a shaft turning in bearings in the lay, a lug thereon, connections between said lever and shaft, and a spring adapted to return the ratchet and lever to their normal positions when the ratchet is engaged by neither of said pawls, whereby when the ratchet is turned a determinate distance said lever and its connections turn the last-named shaft a distance sufficient to cause said lug to engage said ear.
9. In a loom, in combination, a nipper adapted to grasp an end of weft and pull it across the loom, a yarn-carrier adapted to present an end of yarn to the nipper, a ratchet-wheel, an actuating-pawl therefor, the crank-shaft, connections from the shaft to the actuating-pawl adapted to be operated when the nipper fails to insert an end of yarn, a holding-pawl, connections from the shaft to the holding-pawl adapted to release the same after

the actuating-pawl engages the ratchet and return the holding-pawl into operative position before the actuating-pawl disengages, belt-shifting mechanism and connections from the ratchet adapted, when the latter is turned a determinate distance, to engage and operate the belt-shifting mechanism.

10. In a loom, in combination, a nipper adapted to grasp an end of weft and pull it across the loom, a yarn-carrier adapted to present an end of yarn to the nipper, a lever, the crank-shaft, connections from the shaft to the lever adapted to be operated when the nipper fails to insert an end of yarn, the take-up mechanism, connection thereto from the lever adapted when operated by the lever to render the take-up mechanism inoperative, a second lever, connections from the first lever to the second lever to move the latter when the former is operated, means to hold the second lever in the position to which it is moved by the first lever, belt-shifting mechanism, and connections from the second lever to the belt-shifting mechanism whereby the former operates the latter.

11. In a loom, in combination, a nipper adapted to grasp an end of weft and pull it across the loom, a yarn-carrier adapted to present an end of yarn to the nipper, a belt-shifting control-lever, a belt-shifting lever operated by the latter, a tripping-lever adapted to operate the belt-shifting control-lever, an ear on the tripping-lever, a shaft on the lay, a lug on the shaft adapted when the shaft is turned a predetermined extent to move said lug into position to engage the ear in the movement of the lay, and mechanism connected with said shaft and adapted to be operated when the nipper fails to insert an end of yarn a predetermined number of consecutive times.

12. In a loom, in combination, a nipper adapted to grasp an end of weft and pull it across the loom, a yarn-carrier adapted to present an end of yarn to the nipper, the take-up mechanism, a ratchet-wheel, an actuating-pawl therefor, a holding-pawl therefor, the crank-shaft, connections from the shaft to the actuating-pawl adapted to be operated when the nipper fails to insert an end of yarn, connections from the actuating-pawl to the take-up mechanism adapted when operated to render the take-up mechanism inoperative, belt-shifting mechanism, connections from the ratchet-wheel adapted, when the ratchet-wheel is turned a determinate distance, to engage and operate the belt-shifting mechanism, mechanism to release the holding-pawl, and means, operating with the belt-shifting mechanism, to actuate the holding-pawl release mechanism.

13. In a loom, in combination, a nipper adapted to grasp an end of weft and pull it across the loom, a yarn-carrier adapted to present an end of yarn to the nipper, a ratchet-

wheel, an actuating-pawl therefor, the crank-shaft, connections from the shaft to the actuating-pawl adapted to be operated when the nipper fails to insert an end of yarn, 5 a holding-pawl, means to release the holding-pawl after the actuating-pawl engages the ratchet and to return the holding-pawl into operative position before the actuating-pawl disengages, a spring adapted to return the 10 ratchet to its normal position when engaged by neither of said pawls, belt-shifting mechanism, connections from the ratchet adapted, when the latter is turned a determinate distance, to engage and operate the belt-shifting mechanism, and means, operating with the belt-shifting mechanism, to actuate the means controlling the holding-pawl and thereby release said pawl.

14. In a loom, in combination, a nipper 20 adapted to grasp an end of weft and pull it across the loom, a yarn-carrier adapted to present an end of yarn to the nipper, a ratchet-wheel, an actuating-pawl therefor, the crank-shaft, connections from the shaft 25 to the actuating-pawl adapted to be operated when the nipper fails to insert an end of yarn, a holding-pawl, connections from the shaft to the holding-pawl adapted to release the same after the actuating-pawl engages the 30 ratchet and return the holding-pawl into operative position before the actuating-pawl disengages, belt-shifting mechanism, connections from the ratchet adapted, when the latter is turned a determinate distance, to engage and operate the belt-shifting mechanism, and means, operating with the belt-shifting mechanism, to engage the connections from the shaft to the holding-pawl, thereby releasing said pawl.

40 15. In a loom, in combination, a nipper adapted to grasp an end of weft and pull it across the loom, a yarn-carrier adapted to present an end of yarn to the nipper, a lever, the crank-shaft, connections from the shaft 45 to the lever adapted to be operated when the nipper fails to insert an end of yarn, the take-up mechanism, connections thereto from the lever adapted when operated by the lever to render the take-up mechanism inoperative, a 50 second lever, connections from the first lever to the second lever to move the latter when the former is operated, means to hold the second lever in the position to which it is moved by the first lever, belt-shifting mechanism, connections from the second lever to the belt-shifting mechanism whereby the former operates the latter, and means, operating with the belt-shifting mechanism, to move the holding means for the second lever 55 into inoperative position.

16. In a loom, in combination, a nipper adapted to grasp an end of weft and pull it across the loom, a yarn-carrier adapted to present an end of yarn to the nipper, the take-

up mechanism, a ratchet-wheel, an actuating-pawl therefor, a holding-pawl therefor, the crank-shaft, connections from the shaft to the actuating-pawl adapted to be operated when the nipper fails to insert an end of yarn, connections from the actuating-pawl to the 70 take-up mechanism adapted when operated to render the take-up mechanism inoperative, belt-shifting mechanism, connections from the ratchet-wheel adapted, when the ratchet-wheel is turned a determinate distance, to engage and operate the belt-shifting mechanism, a cam on said shaft, a lever actuated by the cam, connections from the lever to the holding-pawl adapted, when operated by the lever, to release said pawl, and a second lever 75 operating with the belt-shifting mechanism and adapted to engage and operate the first lever, thereby effecting the release of said pawl.

17. In a loom, in combination, a yarn-carrier, a finger, a nipper adapted to grasp an end of yarn and pull it across the loom, means to lift said yarn-carrier at the warp-inserting movement of the nipper, thereby causing the yarn to engage and lift the finger, the take-up mechanism, and means controlled by the finger to render the take-up mechanism inoperative when the finger is not lifted.

18. In a loom, in combination, a yarn-carrier, a finger, a nipper adapted to grasp an 95 end of yarn and pull it across the loom, a cam, connections thereto from the yarn-carrier adapted to lift the same at the warp-inserting movement of the nipper, thereby causing the yarn to engage and lift the finger, a lever 100 operated by the finger, the take-up mechanism, the crank-shaft, and connections including said lever from the crank-shaft to the take-up mechanism to render the latter inoperative when said finger is not lifted.

19. A nipper for haircloth-loom comprising, in combination, a fixed jaw, a spring-pressed movable jaw, one of said jaws having a recess, and a spring-plate overlying said recess and separated therefrom by a space.

20. A nipper for haircloth-loom comprising, in combination, a fixed jaw, a spring-pressed movable jaw, one of said jaws having two recesses of different depths, and a spring-plate of a thickness substantially equal to the depth of the shallower of said recesses and inset therein and overlying the deeper recess.

21. A nipper for haircloth-loom comprising, in combination, two jaws, and a spring-plate secured in the gripping-face of one of 120 said jaws.

In testimony of which invention I have hereunto set my hand, at Philadelphia, on this 30th day of May, 1905.

GEORGE S. COX.
